UNITED STATES PATENT OFFICE.

JAMES S. PARRISH, OF CLARKSVILLE, ASSIGNOR TO CHARLES B. PARRISH,
OF MONTGOMERY COUNTY, TENNESSEE.

TOILET APPLIANCE.

SPECIFICATION forming part of Letters Patent No. 416,489, dated December 3, 1889.

Application filed September 2, 1889. Serial No. 322,729. (No model.)

To all whom it may concern:

Be it known that I, JAMES S. PARRISH, a citizen of the United States, residing at Clarksville, in the county of Montgomery and State 5 of Tennessee, have invented certain new and useful Improvements in Toilet Appliances; and I do hereby declare the following to be a full, clear, and exact description of the invention, such as will enable others skilled in the art to which it appertains to 10 make and use the same.

This invention relates to hair-dressing appliances; and its object is to enable a lady's hair to be properly spread and dried after 15 the same has been washed.

In the accompanying drawings, wherein like letters represent like parts, Figure 1 is a perspective view showing the method of using the invention; Fig. 2, a detached perspective showing the form and construction of the device, and Fig. 3 a similar view showing the position of the supports of the device when applied to the person of the wearer.

A is a wire frame, bent and curved in the 20 form and manner shown, and provided with the bars B, to spread and support the strands of hair intended to be dried. Arms C, turning outward and inward within the pivot-

hinges a, enable the frame to be attached to the back and supported by the shoulders of 30 the wearer in the manner shown.

It is to be observed that the front part of the frame A is so curved as to approximately conform to the curvature of the back of the wearer, and that the rear part of said frame 35 is set at such an angle to the front part as to hold the mass of back hair clear of the garments of the wearer, and to enable the air to circulate among the under strands of the hair, and so to assist in the drying and puri- 40 fication of the same.

The modes of attachment and use are so simple and obvious as to call for no further description.

Having sufficiently described my invention, I claim as follows:

As a new article of manufacture, the wire frame A, provided with the bars B, the arms C, and the hinges a, substantially as and for 50 the purposes described.

In testimony whereof I affix my signature in presence of two witnesses.

JAS. S. PARRISH.
